SHOE FITTING DEVICE

Elmer Jared Bliss, Chilmark, Mass.

Application February 20, 1942, Serial No. 431,719

7 Claims.

(Cl. 33—3)

This invention relates to shoe fitting devices of a character embodying spring foot-calipers by which the length and width of a foot of a person to be fitted with shoes as well as the inside length of the shoe itself may be determined.

The present invention is an improvement of the apparatus disclosed in my United States Letters Patent No. 1,921,997, granted Aug. 8, 1933 for Shoe fitting devices, by which the length of a foot to be fitted with shoes and the longitudinal dimension of the foot-area provided by a particular shoe might be gauged either simultaneously or selectively for comparison thereof, the measurements of both shoe and foot thus obtained being registered upon a scale in terms of shoe sizes. The device herein disclosed embodies the principal features of said patented apparatus in combination with certain improvements hereinafter set forth.

A principal object of the improved apparatus hereof is the provision of calipers having a pair of pivoted arms adapted for engagement of the heel and toe, respectively, of a foot interposed between the arms, or of the opposite sides of the foot at its widest point, for gauging the dimensions of the foot while carrying the weight of the body of the person to be fitted, and embodies a support for the heel of the foot when positioned between the caliper arms for measuring the width whereby the measurements may be obtained with the foot supported and arranged with respect to its normal load in the same manner as when encased in a properly fitted shoe.

More specifically it is the object to provide a pair of arms pivoted together intermediate their ends, forming one pair of calipers by the use of which the length and width of the foot to be fitted may be determined, and another pair of calipers adaptable for measuring the interior length of the shoe.

Another object is to provide support for a heel of a foot when the latter is arranged for measurement of foot width, pivoted at the vertex of the angle formed between pivoted arms comprising calipers, to facilitate more accurate alignment of the foot which respect to the area between the caliper arms.

Another object is the provision of a pair of scales coordinated with both width and length size-designations of shoes required for proper fitting of feet gauged by the device, in conjunction with pointers, movable in response to adjustment of the caliper arms of the device for the accommodation of a foot of a customer, to indicate the size of shoe required to fit properly the foot so gauged.

Another object is to provide an expandible device adapted for insertion into a shoe for indicating the length of the foot-area furnished by a shoe, incorporating a laterally adjustable toe

gauge to compensate for variations in toe widths of feet to be fitted.

Still another object is to provide a holder arranged to support a card carrying an arcuate scale of shoe sizes delineated thereon in the arc of movement of either or both of the indicator pointers, the latter being equipped with a means for marking the scale of the card adjacent the size-designation thereon which indicates the size of shoe required to fit the foot being measured to establish a permanent record thereof.

The above and other objects, such for example as simplicity and ease of operation, marked sensitivity to slight variations in size of foot and shoe, and durability will be apparent to those to whom this specification is directed, from a reading of the following description, reference being had to the accompanying drawings in which:

20 Fig. 1 is a plan view of a device embodying my invention illustrating its use for simultaneously determining and comparing the length of a foot and of the foot-area provided by a shoe;

25 Figs. 2 and 3 are sectional views taken on correspondingly-numbered lines of Fig. 1;

Fig. 4 is a broken plan view of the indicator and card holder associated therewith for registering the width size of a foot measured;

30 Fig. 5 is a plan view, similar to Fig. 1; indicating the use of the apparatus when measuring the width of a foot;

35 Fig. 6 is a sectional view taken on lines 6—6; of Fig. 5 illustrating particularly the means for punching the card for marking the width size thereon;

40 Fig. 7 is a plan view of the toe gauge, taken from the top thereof as indicated in Fig. 5, depicting its adjustment and position in a shoe having a narrow toe, the outline of which is shown in dotted lines;

Fig. 8 is a plan view, similar to Fig. 7, illustrating the toe gauge with the parts thereof in other relative positions.

Referring to the drawings in detail, the numerals of which indicate similar parts throughout the several views, 10 and 11 designate generally the members, respectively, of a pair thereof pivoted together intermediate their ends on a transverse pin 12. A heel support 13 is threaded on the upper end of pin 12. The heel support 13 is curved downwardly as at 14 into one of the angles formed between the members 10 and 11, the sides of which angle comprise foot-caliper arms 15 and 16. An arcuate heel guard 17 is integrally formed with the heel support 13 at the opposite edge thereof from the downwardly sloping portion 14, to delineate the position of the heel of a foot when the device is to be used for measuring the width of the foot. A pair of plates 60 18, integral with the respective arms 15 and 16,

diverge outwardly from heel support 13 to engage opposite sides of a foot interposed therebetween at its widest point when positioned on the heel support and extending between the foot-caliper arms 15 and 16.

From the plate 18 each of arms 15 and 16 curve outwardly in relatively diverging arcs, terminating (respectively) in arcuate upstanding heel and toe guards 19, which are utilized in measuring the length of a foot, as is hereinafter described.

At the opposite side of the pivot pin 12 from the width and length foot-calipers 15 and 16 the member 11 is curved outwardly to provide a shoe caliper arm 20 terminating in a rounded tip 21. The member 10 extends from the pivot pin 12 on a line substantially bisecting the angle formed between the foot-caliper arms 15 and 16 and is then curved sharply away from the arm 20 to provide a shoe caliper arm 22 complementary to the arm 20. The outer end of arm 22 is flattened to form a bearing surface for pivotal support of an adjustable toe gauge generally indicated by the numeral 23 and comprising a pair of fingers 24, pivoted on a pin 25 mounted on the flat surface of the arm. A knurled nut 26 threaded on the upper end of pin 25 is adapted by rotation to clamp fingers 24 in an adjusted position relative to each other and to arm 22. The opposed surfaces 27 of fingers 24 are preferably flat and parallel to one another so as to fit snugly together and provide when so engaged a rounded end 28 for the arm. Fingers 24 may be spread apart to conform generally to the toe length and width of a foot to be fitted in order to enable gauging of the foot-area of a shoe as qualified by the contour of a particular foot to be accommodated, as is later described.

Integral with the member 11 and extending laterally from the point of pivoting of the members 10 and 11 is a pointer 29 which overhangs and is moved across a scale plate 30 integral with and extending laterally from the caliper arm 15 of member 10. A pair of scales 31 and 32 are delineated on the scale plate 30 in arcs having their centers on the pivot pin 12. A stop 33 is mounted on the edge of scale plate 30 for the abutment of pointer 29 to limit the movement of the pointer in one direction at the edge of scales 31 and 32 as well as the movement of the arms of the respective calipers 15-16 and 20-22 toward one another. The pointer 29 is normally held against stop 33 by a helical spring 34 interposed between and secured to the shoe caliper arms 20 and 22. The scale 32 is graduated to indicate in inches the inside length of the shoe as gauged by the spread of the arms 20 and 22 when positioned in a shoe with the toe gauge 23 and heel tip 21 contacting the toe and heel of the shoe, respectively. The calibrations of scale 31 are arranged and identified in terms of shoe sizes whereby the pointer registering therewith will indicate the length-size graduation of a shoe required to fit a foot interposed between the toe and heel guards 19 of the arms 15 and 16, as well as of a shoe having an inside length equal to the distance between the ends of the shoe-caliper arms 20 and 22 which will be variably spaced in accordance with the adjustment of the arms 15 and 16 or with the registry of the pointer 29 with a particular scale calibration.

A three-sided frame 35 is riveted or otherwise secured to the scale plate 30 below the scales 31 and 32 to receive a card 36 (Fig. 1) carrying a pair of scales 37 and 38 which are identical with scales 31 and 32 marked on the plate 30. The

outer end of pointer 29 is formed with a transverse opening in which a vertically slidable punch 39 is disposed. A spring 40 encircles punch 39 between the head 41 thereof and pointer 29 to normally support the lower end of the punch above plate 30 to permit the insertion of a card into frame 35. Upon adjustment of the caliper arms 15 and 16 in accordance with the use of the device, as hereinafter more fully described, the location of the pointer 29 over the scales 37 and 38 carried by card 36 may be marked thereon by depression of the punch 39, the scale plate being slotted as at 42 beneath the arc of movement of punch 39 to permit the latter to transfix the card. A second pointer 43 is pivoted to scale plate 30 adjacent the upright width plate 18 of the adjoining foot-caliper arm 15 to register with an arcuate width scale 44 delineated on the outer edge of plate 30. The calibrations of the scale 44 are identified by letters A to E in accordance with the usual manner of designating shoe widths. The pointer 43 is actuated by a lever 45 pivoted to pointer 29 adjacent the outer end of the latter and to the pointer 43 adjacent the pivoted end thereof so that the width-size indicated thereby is co-ordinated with the width-size of a shoe adapted to fit a foot gauged by the width plates 15. A card frame 46 similar to frame 35 is secured to scale plate 30 adjacent to scale 44 to receive and retain a card 47 (Fig. 1) having a scale 48 of shoe width-sizes printed thereon, which with card 47 positioned in frame 46 will be superimposed on the scale 44. The scale plate 30 is slotted as at 49 adjacent scale 44 to receive the lower end of a punch 50 carried slidably for transverse movement against the card 47, by the pointer 43. Spring 51 encircles punch 50 between the head 52 thereof and pointer 43 to resiliently urge the punch to its uppermost position and enable the insertion and removal of card 47 from frame 46.

The use and operation of my invention is briefly described as follows:

To determine the length of a customer's foot in terms of shoe length-sizes or to compare the length of a foot with the foot-area provided by a shoe the customer's unshod foot is placed between the heel and toe guards 19 carried by the ends of the caliper arms 15 and 16. The spread of these arms necessary to accommodate the customer's foot will shift pointer 29 associated with one of the members, i. e., member 11, across the scale 31 delineated on plate 30, integral with the other member 10, so as to register with the calibration of said scale which indicate the length-size of shoe required to fit the foot thus engaged. While the customer's foot is still positioned between the foot-caliper arms, a shoe marked with the required size as indicated by the pointer on the scale may be tested for size to satisfy the customer by the use of the shoe caliper arms 20 and 22, as is about to be described.

As the toe contour of the feet of different persons differs considerably, more or less room is required in the toe of the shoes to afford proper fit. Preliminarily to gauging the shoe selected, by the calipers 20 and 22, the knurled nut 26 is loosened and finger 24 are spread or confined in accordance with the area required in the extreme forepart of the shoes, as determined by the sales-clerk, in the toe of a properly fitted shoe for accommodation of the toes of the customer. Nut 26 is then tightened and the toe gauge 23 on the end of arm 22 is inserted into the toe of the shoe for disposition at the foremost end thereof. If

the shoe is of a size adapted for a customer's foot the heel tip 21 of arm 20 will fit snugly into the heel of a shoe, thus demonstrating to the customer not only the accuracy of the sales-clerk's selection of the shoes needed to fit the customer, but also will indicate on scale 32 the length in inches of the foot-area of the shoe, and on the scale 31 the length-size of the shoe. It will be apparent that the operation of measuring the shoe with the caliper arms 20 and 22 need not be performed while the foot of the customer is interposed between the arms 15 and 16; that after obtaining a reading on the scale 31, incidental to the gauging of the foot by the arms 15 and 16, the foot may be withdrawn, and the pre-adjustment of the spread of the caliper arms 20 and 22 as a prerequisite to measuring the shoe may be determined by resetting the pointer 29 to the calibration indicated on the scale 31 obtained while measuring the foot.

With the length of the shoe required for a proper fit thus determined, the device is placed on the floor or other suitable foundation and the unshod foot of the customer is placed between the width plates 18 and the heel of the foot on the support 13 therefor and abutting against the heel guard 17. The weight of the customer's body should be equally distributed so that the foot will normally assume the size and shape it normally takes in a properly fitted shoe with the customer standing. The spring 34, normally tending to draw the caliper arms 15 and 16 together, causes the plates 18 to assume close contact with opposite sides of the widest portion of the foot. Coincidentally with the spread of the foot-caliper arms for the interposition of the foot between the plates 18 the pointer 43 will have been moved across the scale 44 by lever 45 in response to movement of the pointer 29 relative to arm 15. The width of the shoe required to fit the customer's foot will thus be indicated by the pointer 43 on the scale 44. Cards 36 and 41 carrying the scales as above described, may be inserted in frames 35 and 46, respectively, and pierced by the punches 39 and 50 at the calibrations over which the pointer 29 and 43 are positioned.

While the device may be operable without the cards the use of the latter enables the clerk or customer to obtain a permanent record of the size of a properly fitted shoe.

It will be understood that while in the foregoing illustrated description I have described but one embodiment of my invention and have catalogued certain features, advantages and uses inherent therein, I do not limit myself to the particular embodiment shown and described, it being obvious to those of skill in the art to which my invention appertains that numerous changes may be made in size, design, proportion or number of the various parts, and that the essence of my invention is capable of many modifications, without departing from the scope of my invention as defined by the claims appended hereto.

What I claim and desire to secure by Letters Patent is:

1. In a device of the character described, a pair of arms pivoted to one another intermediate their ends, and a heel stop connected to said arms adjacent their point of pivoting, opposed

portions of said arms spaced from said heel support being formed to receive therebetween the ball of the foot for gauging the width of the foot.

2. In a device of the character described, a pair of arms pivoted to one another intermediate their ends, a heel stop carried by one of said arms adjacent the point of pivoting of the latter, opposed portions of said arms spaced from said heel support being shaped to receive therebetween the ball of the foot for gauging the width of the foot, and an indicator to indicate the width size of a shoe adapted to fit a foot gauged by said arms.

3. In a device of the character described, a pair of arms pivoted to one another, and a heel support pivoted at its center to said arms at the point of intersection of the latter whereby the middle of said heel support is adapted to coincide with a line bisecting the angle formed by said arms throughout the range of movement of the latter.

4. In a device of the character described, a pair of arms pivoted to one another, and a heel support pivoted at its center to said arms at the point of intersection of the latter whereby the middle of said heel support is adapted to coincide with a line bisecting the angle formed by said arms throughout the range of movement of the latter, opposed portions of said arms being formed to contact the sides of a foot positioned therebetween with the heel of the foot on said heel support to gauge the width of the foot.

5. In a device of the character described, a pair of arms pivoted to one another, a heel support pivoted at its center to said arms at the point of intersection of the latter whereby the middle of said heel support is adapted to coincide with a line bisecting the angle formed by said arms being formed to contact opposite sides of the latter, opposed portions of said arms being formed to contact the sides of a foot positioned therebetween with the heel of the foot on said heel support to gauge the width of the foot, and an indicator actuated by adjustment of said arms to indicate the width of a foot contacted by said opposed portions of said arms.

6. In a device of the character described, a pair of arms pivoted to one another, a heel support carried by said arms, opposed portions of said arms being found to contact opposite sides of a foot partially supported by said heel support to gauge the width of the foot, a card frame carried by one of said arms, and an indicator carried by the other of said arms to move across a card disposed in said frame so as to indicate thereon the width of the foot engaged by said arms.

7. In a device of the character described, a pair of arms pivoted to one another, a heel support carried by said arms, opposed portions of said arms being formed to contact opposite sides of a foot partially supported by said heel support to gauge the width of the foot, a card frame carried by one of said arms, an indicator carried by the other of said arms to move across a card disposed in said frame so as to indicate thereon the width of the foot engaged by said arms, and means carried by said indicator to mark on the card the width size of a shoe adapted to fit the foot contacted by said arms.

ELMER JARED BLISS.

CERTIFICATE OF CORRECTION.

Patent No. 2,326,820.

August 17, 1943.

ELMER JARED BLISS.

It is hereby certified that error appears in the printed specification of the above numbered patent requiring correction as follows: Page 3, second column, lines 39, 40 and 41, claim 5, strike out the words "arms being formed to contact opposite sides the latter, opposed portions of said arms being formed to contact" and insert instead --arms throughout the range of movement of the latter, opposed portions of said arms being formed to contact--; line 50, claim 6, for "found" read --formed--; and that the said Letters Patent should be read with this correction therein that the same may conform to the record of the case in the Patent Office.

Signed and sealed this 14th day of December, A. D. 1943.

(Seal)

Henry Van Arsdale,
Acting Commissioner of Patents.
